AUTOMATIC ELECTRIC TOASTER

Bror G. Olving, Elgin, Ill., assignor to McGraw Electric Company, Elgin, Ill., a corporation of Delaware

Application May 5, 1945, Serial No. 592,135

12 Claims. (Cl. 219—19)

1

My invention relates to electric crisping and toasting devices and particularly to timing means for such appliances.

An object of my invention is to provide a timing means and an electric circuit therefor which are dependable and which will stand up in service for a relatively long period of time.

Another object of my invention is to provide a timing means, the performance of which depends upon the inherent electrical characteristics of its component parts and the operation of which is not dependent on or controlled by any energy supplied from mechanical or thermal storage devices.

Still another object of my invention is to provide a timing means and an electric circuit therefor including an electron tube to obtain the above mentioned operation.

Yet another object of my invention is to provide an electric circuit comprising an electron tube as well as means for gradually charging an electrostatic condenser connected to the tube to thereby cause an increasing current to traverse the tube, which current operates electric relays to predetermine the time period of crisping and of toasting in that order.

Other objects of my invention will either be apparent from a description of one circuit embodying my invention or will be pointed out during the course of such description and set forth in the appended claims.

In the drawings,

Figure 1 is a view in side elevation of a toaster embodying my invention.

Fig. 2 is a front elevational view of the device shown in Fig. 1, Figs. 1 and 2 being shown on a reduced scale.

Fig. 3 is a vertical, longitudinal, sectional view taken on the line 3—3 of Fig. 4.

Fig. 4 is a vertical, lateral, sectional view taken on the line 4—4 of Fig. 3.

Fig. 5 is a fragmentary horizontal, sectional view taken on the line 5—5 of Fig. 4.

Fig. 6 is a diagram of connections for the timing elements shown in Figs. 3, 4 and 5.

Fig. 7 is a graph showing time periods for various grid bias voltages of the electron tube of Fig. 6.

Fig. 8 is a graph showing current values for various grid bias voltages of the electron tube shown in Fig. 6, and,

Fig. 9 is a series of graphs showing plate characteristics of the electron tube shown in Fig. 6.

Referring first of all to Figs. 1 to 5 inclusive,

2

I have there shown a domestic two-slice toaster designated generally by numeral 11 which includes a bottom frame member 13 which may preferably but not necessarily be made of molded composition material. I provide positioned against the upper surface of member 13, a metal bottom or base plate 15, as well as an outer casing 17 having an open top and bottom, and a cover 19 suitably secured to the top portion of the outer casing 17.

I have elected to show a two-slice toaster which is provided with a pair of openings 21 through the cover 19 through which fresh slices of bread may be dropped into the toaster casing and through which toasted slices of bread may be removed, all as is well known in the art.

I provide two pairs of planar, vertically-extending toast heating elements 23, each one of which comprises one or more sheets 25 of electric-insulating material such as mica, on which is wound a strip 27 of a suitable electric resistance material. The means for and method of supporting the pairs of toast heating elements 23 may be any desired or suitable kind now well known in the art. I provide a rear intermediate wall 29 and a front intermediate wall 31 which cooperate with the inner of each of the pairs of toast heating elements 23 and each of the outer baffle plates 33 to constitute a toasting chamber.

I provide further a bread carrier 35 in each of the toasting chambers, the rear end portion of each carrier 35 being adapted to move vertically upwardly and downwardly in a slot in the rear intermediate wall 29 while the front end portion of each of said carriers is secured to rearwardly bent end portions of a rear carriage plate 37. I provide further a front carriage plate 39 which is spaced from and secured to the rear carriage plate 37 by a plurality of headed studs 41, each of which is secured in substantially a corner portion of the front carriage plate 39. I provide further a plurality of grooved rollers 43 on each of the headed studs 41 between the front and the rear carriage plates, which rollers are adapted to move upwardly and downwardly against the inner surface of a pair of vertical rods 45, the lower end portions of which are adapted to fit into the base plate 15 while the upper reduced end portions thereof are adapted to fit into the front end portions of a pair of frame plates 47 and in a cross bar 49 provided to insure that the horizontal distance between the two rods 45 will not vary during the life of the appliance.

Since it is desired to normally yieldingly maintain the bread carriers 35 in their upper or non-toasting position, I provide a tension coil spring 51, the upper end portion of which is secured to a lug or bracket 53 secured against the upper end portion of the front intermediate wall 31 while the lower end of spring 51 is secured to a rearwardly extending lug 55 constituting a part of the front carriage plate 39. This will therefore yieldingly bias the bread carriers into their upper or non-toasting positions.

Means for moving the bread carriers as well as the carriage plates to their lower or toasting position shown in Fig. 3 by broken lines, comprise a bar 57 secured against the front surface of the front carriage plate 39 and extending through a slot in the front wall of the outer casing 17 and being provided with an actuating knob 59 secured thereon outside of the casing 17. Pressure on the knob by an operator will cause downward movement of the bread carriers and the parts operatively associated therewith into their lower or toasting positions where they will be held by the engagement of a projection 61 secured against the front surface of the front carriage plate 39 with a hook-shaped end 63 secured to the upper end portion of a resilient bar 65 which has its lower end mounted on a bracket 67, of substantially U-shape, which is secured against the upper surface of base plate 15.

A pair of fixed contacts 69 and 71 are supported on a block 73, of electric-insulating material, which is supported from the front intermediate wall by a bracket 75. A contact bridging member 77 is insulatedly supported as by a resilient arm 78 from the rear carriage plate 37 as by a block 79, of electric-insulating material. I provide further a pair of upper fixed contacts 81 and 83 which are supported on a block 85 of electric-insulating material, which block is supported by a bracket 87 secured against the front surface of the front intermediate wall 31. The purpose and use of the upper fixed contacts 81 and 83 will hereinafter appear.

Referring now to Fig. 6 of the drawings, I have there illustrated a system of control for an improved crisper and toaster, which system comprises a pair of supply circuit conductors 89 and 91 of which supply circuit conductor 89 is connected to one terminal of one of the toast heating elements 23, each pair of which positioned in a toasting chamber may be connected in series electric circuit with each other.

I provide further an electron tube 93 which is preferably a power amplifier tube of the triode type and which has a relatively high vacuum. The tube includes a plate anode 95, a control grid 97, a cathode 99 and a filament 101. When the filament of such a tube is energized and direct current potential of the proper polarity is impressed upon the plate and cathode, current will pass through the tube if the negative grid-bias voltage is within the proper range. If the grid-bias voltage is made less negative, more current will pass through the tube, that is a decrease in the negative grid-bias voltage will produce an increase in the plate to cathode current.

A voltage doubler bridge of the conventional type is provided which has been designated by numeral 103. This bridge comprises two half-wave rectifiers 105 and 107 and two electrostatic condensers 109 and 111, the two rectifiers 105 and 107 being connected in opposition to each other in such a manner that when an alternating current voltage is impressed across the terminals

5
10
15

113 and 115 thereof, direct current of approximately double the peak voltage of said A. C. line voltage will appear across the terminals 117 and 119, terminal 117 being of positive polarity and terminal 119 being of negative polarity. At the same time one-half of the above mentioned D. C. voltage will appear between terminals 117 and 115, terminal 117 being positive with respect to terminal 115 and the other half of the voltage will appear between terminals 115 and 119, terminal 115 being positive with respect to terminal 119 but negative with respect to terminal 117. An adjustable potentiometer 121 has its two terminals connected to terminals 119 and 115 and is provided with a manually-adjustable contact arm 123.

I provide also a timing condenser 125 as well as a timing resistor 127, the timing resistor 127 having a negative temperature coefficient of resistance and being subject to heat from one or more of the toast heating elements 25. The capacitance of the condenser 125 may be on the order of 6 microfarads and the resistance of resistor 127 may be on the order of 10 megohms. The timing condenser 125 has one terminal thereof connected to the manually-adjustable contact arm 123 while its other terminal is connected to one terminal of the timing resistor 127 by a conductor 129, while the other terminal of timing resistor 127 is connected by a conductor 131 with a conductor 133 which connects terminal 115 of the voltage doubler bridge with one terminal of the heated filament as well as with the terminal of the cathode 99. The other terminal of the timing condenser 125 is also connected to the control grid 97. Terminal 113 of the voltage doubler bridge is connected by a conductor 135 with supply circuit conductor 89. I provide a third heating or crisping element 127 which, as is shown, particularly in Figs. 3 and 5 of the drawings, may be split in two halves, each half being positioned below each slice of bread when the bread is in its toasting position and mounted on a strip 138, of electric-insulating material. I provide an electromagnetic latch release which includes a coil 139, a vertically-movable armature core 141 connected to the free end of a bell crank lever 143 which is pivotally mounted on a pivot pin 145 supported by member 67, the longer vertically extending arm of bell crank lever 143 being adapted to engage the hook-shaped end portion 63 and cause it to move out of engagement with member 61. Coil 139 may be supported by member 67.

100

I provide further two electromagnetic relays 146 and 147, of which relay 146 includes a coil 149, a vertically-movable armature core 151 and a contact bridging member 152, which is adapted to engage with and be disengaged from the fixed contacts 153 and 155. One terminal of the crisping heater 137 is connected to one terminal of the second toast heating element 23 by a conductor 157, which conductor 157 is connected by a conductor 159 with fixed contact 153. Fixed contact 155 is connected by a conductor 161 to the other terminal of the crisping heating element 137.

Relay 147 comprises a coil 163, an armature core 165, a contact bridging member 167 which is adapted to engage with and be disengaged from two fixed contacts 169 and 171. The two upper terminals of coils 149 and 163 are connected by a conductor 173, while the lower terminal of coil 149 is connected by a conductor 175 with the plate anode 95, while the lower terminal of coil 163 is connected by a conductor 176 with terminal 117.

of the voltage doubler bridge. Fixed contact 169 of the second relay is connected to supply circuit conductor 89, by conductors 177 and 135, while fixed contact 171 is connected by a conductor 181 with the lower terminal of coil 139. The upper terminal of coil 139 is connected to fixed terminal 69 of the main switch by a part of a conductor 183 and a conductor 185, while the other fixed terminal 71 of the main switch is connected to the second supply circuit conductor 91 by a conductor 187. The fixed contact 69 is also connected to terminal 115 of the voltage doubler bridge 103 by conductor 183 and to one terminal of the third or crisping heating element 137 by conductor 189. The upper fixed contact 81 is connected to conductor 189, while the other upper fixed contact 83 is connected by a conductor 191 with the upper terminal of timing resistor 127. The filament 101 has one of its ends connected to a resistor 193, the other terminal of which is connected to conductor 177. Upon closing the main switch the voltage doubler bridge 103 is therefore energized through a circuit traceable as follows: from supply circuit conductor 89 through conductor 135, through the bridge to terminal 115; through conductor 183, through the fixed contacts 69 and 71 and contact bridging member 77, through conductor 187 to the other supply circuit conductor 91. The three toast heating elements 23, 23 and 137 are energized through a circuit traceable as follows: from supply circuit conductor 89 through toast heating elements 23, 23 and 137 through conductor 189, through the engaged fixed contacts and contact bridging member and through conductor 187 to the other supply circuit conductor 91.

The second relay 147 has connected in shunt circuit therewith a fixed resistor 195 in addition to an adjustable resistor 197, which latter resistor has a manually-adjustable contact arm 199 which is connected to the lower terminal of coil 163, while the upper terminal of coil 163 is connected to one terminal of resistor 195.

Let it now be assumed that a user of the crisping and toasting appliance desires to make use thereof. He will then drop one or two slices of bread into the toaster and then push downwardly on knob 59 to start the crisping operation. Current will flow from supply circuit conductor 89 through toasting heaters 23 and the crisping heater 137 in series, then through conductors 189 and 185, contact bridging member 77 and conductor 187 to the other supply circuit conductor 91. Since the crisping heater 137 is fully energized while the toasting heaters 23 are not, crisping of the slice or slices of bread will take place to a desired degree, as will be hereinafter set forth, when the crisping heater is short circuited so that the toasting heaters will be fully energized and cause browning or toasting of the slice or slices of bread being treated to a desired degree, all as will be hereinafter set forth.

The voltage doubler bridge is then energized and direct current voltage is impressed across the potentiometer 121 and a charging current begins to flow to the timing condenser through a circuit traceable as follows: from the rectifier terminal 115, through conductors 133 and 131 to and through the timing resistor 127, through conductor 129 to one terminal of the timing condenser 125 and from there to the adjustable arm 123 and back to the potentiometer. This charging current produces a voltage drop across the resistor 127, which voltage drop is impressed between the grid 97 and the cathode 99 of tube 93.

The polarity of the adjustable arm 123 of the potentiometer is negative with respect to that of the terminal 115 and the voltage impressed on the grid 97 is therefore negative with respect to the cathode 99. When first connected there is no charge on the timing condenser 125 and a relatively large charging current flows through the timing resistor 127 causing a voltage drop in timing resistor 127 equal to the impressed potentiometer voltage. As the charging of the timing condenser 125 progresses, the charging current decays or decreases and the terminal voltage across the timing condenser increases in accordance with the well-known logarithmic law depending upon the time-constant of the capacitance and resistance of the circuit. The drop across the timing resistor 127 and therefore the grid-bias voltage at any time is equal to the difference between the voltage impressed by the potentiometer 121 and the voltage existing across the condenser 125 at the instant of consideration. When the condenser 125 has been fully charged to a voltage equal to the potentiometer voltage no more current flows to the condenser and the grid-bias voltage is then zero.

Referring now to Fig. 9 of the drawings, I have there shown a series of graphs or curves from which it will be seen that as the grid-bias voltage on the tube decreases, that is becomes less negative, the current through the plate circuit increases. For instance, considering a plate voltage of 150 volts in a load line indicated by 205 equal to 2,000 ohms which is the sum of the resistances of coils 149 and 162, it will be seen that if the grid-bias voltage is more than -40 volts negative, no current will flow in the plate circuit, but if the grid-bias voltage is decreased to -30 volts, the plate current is approximately 8 milliamperes, at -20 volts it is 18 milliamperes, at -10 volts it is 31 milliamperes and at 0 grid-bias voltage, a current of about 50 milliamperes will flow in the plate circuit. This variation of plate current with the negative grid-bias voltage is shown by graph 201 in Fig. 8 of the drawings.

Referring now to Fig. 6 of the drawings, the two relays 146 and 147 have their energizing coils connected in series in the plate circuit. When relay 146 closes, the auxiliary heating element 137 located at the bottom of a bread toasting compartment is shorted by conductors 159 and 161 and the contact bridging member 152 engaging the fixed contacts 153 and 155, so that full supply circuit voltage is impressed on the conventional toast heating elements 23. When relay 147 closes, the electromagnetic release mechanism is energized from the supply circuit conductor 91 through conductor 187, through the closed main switch comprising fixed contacts 69 and 71 and the contact bridging member 77, through conductor 185, coil 139, through conductor 181, the engaged contacts 169 and 171 with contact bridging member 167, through conductors 177 and 135 to the other supply circuit conductor 89.

The coil 163 of the second relay 147 is shunted by a circuit comprising fixed resistor 195 and a variable resistor 197. The resistance of coil 163 may be on the order of 1000 ohms and that of resistor 195 may be on the order of 2000 ohms and that of the variable resistor 197 may be on the order of 68,000 ohms. While I give specific values of resistances, it is to be understood that these are illustrative only as the actual values must be matched with the plate resistance of the electron tube employed. The purpose of the resistances 195 and 197 connected in shunt with coil 163 is to

delay the closing of the second relay which terminates the toasting operation by deenergizing the entire toaster.

The first relay 146 may be set to close at 7.5 milliamperes and the relay 147 may be set to close at 30 milliamperes when the adjustable arm 199 of the variable resistor 197 is at its lowermost position, that is when all of the resistors 195 and 197 are in circuit. The current traversing the tube 93 and coil 149 of relay 146 is divided into two parts, the larger part traversing coil 163 while the smaller part traverses the series connected resistors 195 and 197, the values of these currents being inversely proportional to the respective resistances of the two circuits all as well understood. If, for instance, the resistance of coil 163 is 1000 ohms and that of the connected portion of resistor 197 in series with resistor 195 is 9000 ohms, $\frac{1}{6}$ of the plate current will traverse the coil 163 and $\frac{5}{6}$ will traverse the resistors 195 and 197. As the relay 147 is set to close at 31 milliamperes, the plate current must increase to 35 milliamperes before the current through coil 163 is sufficiently large to operate the relay. If the adjustable arm 199 is moved still further in a counter-clockwise direction, the plate current must be still higher before relay 149 closes.

Curve 207 in Fig. 8 shows the plate current in milliamperes corresponding to any negative grid-bias voltage impressed on the electron tube 93. It has been hereinbefore set forth that the grid-bias voltage in the circuit of Fig. 6 at any time is equal to the difference between the voltage impressed by the potentiometer 121 and the voltage existing across the condenser 125 at the instant under consideration. When first connected to the circuit, the condenser 125 has no charge and the grid-bias voltage at that instant is equal to the charging voltage impressed by the potentiometer 121, that is, it is relatively high. The charging of the condenser 125 begins immediately and the grid-bias voltage starts to decrease logarithmically as is well known.

The time required for the grid-bias voltage to decrease from its initial maximum value to any desired lower value is shown by the curves 209, 211 and 213 of Fig. 7. For instance, referring to curve 209, it will be seen that the grid-bias voltage decreases from an initial voltage of -100 volts to -30 volts in 60 seconds while it requires 120 seconds to drop to -9 volts, 185 seconds to drop to -7 volts and 150 seconds to drop to -5 volts. If the initial grid-bias voltage is -54 volts as shown by curve 211, it will take 30 seconds to drop to -30 volts, 90 seconds to drop to -9 volts, 105 seconds to drop to -7 volts and 120 seconds to drop to -5 volts. If the initial grid-bias voltage is -30 volts as shown by curve 213, it will require 60 seconds to drop to -9 volts, 75 seconds to drop to -7 volts, and 90 seconds to drop to -5 volts.

Referring now to curve 209 of Fig. 7, it will be seen that if the initial grid-bias voltage which is the same as the actual potential tapped across potentiometer 121 of Fig. 6 is -100 volts, it will drop to -30 volts in exactly 60 seconds. Referring now to Fig. 8, it will be seen that when the grid-bias voltage has dropped to -30 volts, the plate is 7.5 milliamperes and if the first relay 146 is set to close at this current, this relay will automatically close as soon as the grid-bias voltage drops to -30 volts and the auxiliary heating element 137 will be short-circuited thus terminating the first or crisping portion of the entire cycle. It is to be understood that the resistance of the auxiliary lower resistor 137 is sufficiently high so

that the vertically positioned heating elements 23, one at each side of a slice of bread, will not operate at a relatively high temperature so that little or no toasting of the sides of a slice of bread will be obtained during the first or the crisping portion of the cycle. It is obvious that the entire slice of bread will be subjected to a relatively low temperature conducted heat from not only the lower heater 137 but also from the two side heaters 23. As soon as the auxiliary heating element 137 is short-circuited by means of relay 146, full line voltage is impressed across the side toast heating elements 23 which then increase in temperature subjecting the dried-out slice or slices of bread to comparatively large amounts of radiant heat for the final browning or toasting portion of the cycle.

Referring again to curve 209 in Fig. 7, it will be seen that the grid-bias voltage continues to decrease from -30 volts to -9 volts in 60 additional seconds or from -30 volts to -7 volts in 75 additional seconds, or from -30 volts to -5 volts in 90 additional seconds. Curve 207 in Fig. 8 indicates further that at a negative grid-bias voltage of -9 volts, the plate current is 31 milliamperes, at -7 volts, it is 35 milliamperes, and at -5 volts, the plate voltage is 39 milliamperes. The relay coil 163 is adapted to cause upward movement of contact bridging member 167 when the current traversing it reaches 30.5 milliamperes.

It has been mentioned above that the plate current from tube 93 will be divided into two parts when reaching the second relay 147, one part of the current traversing coil 163 and the other part traversing resistors 195 and 197. The resistance of coil 163 is on the order of 1000 ohms, that of resistor 195 is 2000 ohms, that of resistor 197 to the point engaged by the movable contact arm 199 in Fig. 6 is 5000 ohms and that of the resistor 197 not in circuit is 63,000 ohms. When the adjustable contact arm 199 is at its lowermost point, all of the resistance of resistor 197 is shunted across the coil 163, that is in series with resistor 195 so that only a small part of the plate current passes through resistors 195 and 197. In the latter case when the current through coil 163 reaches its final value of 30.5 milliamperes, the current through the shunted resistor is .5 milliampere so that the relay closes when the plate current reaches 31 milliamperes which occurs exactly 60 seconds after operation of relay 146. If contact arm 199 is moved to substantially the position shown in Fig. 6 of the drawings, the total shunting resistance is 7000 ohms and when the current through coil 163 reaches its final value of 30.5 milliamperes, the current through the shunted resistor is 4.5 milliamperes so that the relay closes when the plate current reaches a total of 35 milliamperes which occurs exactly 75 seconds after relay 146 has operated. Further counter-clockwise movement of contact arm 199 still further increases the length of time before the current value in coil 163 has reached the operating value of 30.5 milliamperes.

Referring now again to Fig. 8 of the drawings, it will be seen that the maximum plate-current traversing the tube 93 occurs when the grid-bias voltage has dropped to zero volts and that this maximum current is 48 milliamperes. If now the resistance shunted across relay coil 163 is less than 1600 ohms, the current traversing coil 163 (the resistance of which is 1000 ohms) would never reach its closing value of 30.5 milliamperes. The fixed resistor 195 having a resistance of 2000 ohms has therefore been provided in series with

the variable resistor 197 and will assure closing of relay 147 even though the adjustable arm 199 of resistor 197 may be turned to its extreme counter-clockwise position.

The resistance of the lower auxiliary resistor 137 is on the order of 3 ohms and that of the two resistors 23 is on the order of 11 ohms. At a supply circuit voltage of 115 volts, this means approximately 90 volts is impressed across the two heating elements 23, while 25 volts is impressed across resistor 137. This insures operation during the first part of the cycle of the main toast heating elements 23 at a relatively low temperature so that the slices of bread in the toasting compartment are subjected to very little radiant heat but to a relatively large amount of convected heat supplied partly by heating elements 23 and partly from the lowermost heating element 137. The crisping part of the cycle is thus initiated as soon as the main switch comprising the fixed contacts 69 and 71 and the contact bridging member 77 has been closed.

Upon closure of the main switch, the filament of tube 93 and the voltage doubler bridge 103 are energized and a charging current begins to flow from the potentiometer 121 to the timing condenser 125 through the timing resistor 127, thus producing a negative grid-bias voltage between the cathode 99 and the control grid 97 of the tube and the initial grid-bias voltage is substantially equal to the voltage supplied by the potentiometer 121. This grid-bias voltage gradually decreases as the timing condenser 125 is charged and when the grid-bias voltage has decreased to -40 volts, a current starts to flow in the plate-circuit of the tube through a circuit traceable as follows: from terminal 115 of the voltage doubler bridge, through conductor 133, to the cathode 99 and then to the plate 95, through conductor 175, through coil 149, through conductor 173, through the coil 163 and the shunting resistors 195 and 197, and through conductor 176 to the positive terminal 117 of the bridge 103. As the grid-bias voltage decreases still further, the plate-current increases until the grid-bias voltage reaches -30 volts at which time the plate-current has increased to 7.5 milliamperes and the first relay 146 operates to short-circuit the auxiliary heating element 137 thereby permitting full line voltage to be impressed on the toast heating elements 23 and terminating the crisping portion of the cycle.

As the toasting operation now proceeds, the grid-bias voltage continues to decrease and the plate-current becomes increasingly higher until sufficient plate-current flows in the circuit to permit a current of 30.5 milliamperes to traverse the coil 163, at which time the second relay is actuated and energizes the detent-release mechanism traversing a circuit as follows: from supply circuit conductor 91, through conductor 187, through the main switch comprising fixed contacts 69 and 71 and the contact bridging member 77, through conductor 185 and a part of conductor 183, through coil 139, the closed contacts of relay 147 and through conductors 177 and 135 to the other supply circuit conductor 89.

When the contact bridging member 77 reaches its uppermost position, it will engage fixed contacts 81 and 83 and the timing condenser is short-circuited so as to insure that there will be no residual charge therein when a subsequent toasting operation is initiated. The circuit closed by engagement of contact bridging member 77 with the upper fixed contacts 81 and 83 may be traced as follows: from the left-hand terminal of condenser 125 to the adjustable arm 123, the part of

potentiometer 121 connected in circuit, through conductors 183 and 189, to contact 81, from there through contact bridging member 77 to the second fixed contact 83 and through conductors 191 and 129 to the other terminal of the condenser 125.

The crisping portion of the toast cycle can be varied by adjusting manually the position of the contact arm 123 of the variable potentiometer 121 as by a knob 215 (Fig. 5). The second or toasting portion of the timing cycle is changeable by the variable resistor 197, effected by a knob 217 (Fig. 5), this toasting part of the cycle beginning when relay 146 is closed to short-circuit the auxiliary heating element 137 and ending when relay 147 closes to cause quick upward movement of the bread carriers and termination of a toasting cycle. It has been found that the time required to obtain a certain degree of toasting or browning by subjecting the slices of bread to radiant heat of relatively high temperature is not to a very great degree dependent on the prior crisping of the bread.

It has been hereinbefore stated that the timing resistor 127, which has a temperature resistance on the order of 10 megohms, has a negative temperature coefficient of resistance and that it is subject to heat from one or more of the upper side toast heating elements. When the temperature of the toaster increases, the resistance of the resistor 127 decreases, the timing condenser charges at a higher rate and the negative grid-bias voltage therefore also decreases at a faster rate thus shortening the length of the toasting cycle. The same comments apply also to compensation for exceedingly high and exceedingly low supply circuit voltages since at exceedingly high voltage applied to the main toast heating elements 23, the temperature of the heat radiated thereby against the timing resistor 127 causes a greater decrease in the resistance of the timing resistor and therefore also shortens the length of a toasting cycle.

Various modifications may be made in the systems embodying my invention without departing from the spirit and scope thereof and all such modifications clearly coming within the scope of the appended claims shall be considered a part of my invention.

I claim as my invention:

1. An electron tube control system for an automatic electric toaster including electric toast heating elements, a normally open control switch for said heating elements, means to close said switch and an electromagnetic release means to cause opening of said switch, said system comprising a grid controlled electron tube, a timing resistor having a negative temperature coefficient of resistance and being subject to heat from said toast heating elements and a timing condenser connected in the grid circuit of said tube and two relays having their coils connected in series electric circuit with each other and with the plate of said tube, one of said relays controlling the crisping period of a slice of bread being treated and the second relay controlling the toasting period of a slice of bread being treated and a source of substantially constant direct current potential and means including said timing resistor, timing condenser and said source of direct current potential for causing a predetermined rate of increase of current traversing said tube and the coils of said relays to determine the lengths of the crisping and of the toasting periods and energization of the electromag-

netic release means to cause opening of the switch.

2. An electron tube control timer for an automatic electric crisping and toasting device, comprising a grid controlled electron tube of the negative grid-bias type, a timing resistor and a timing condenser in the grid circuit of the tube, two relays operating at different predetermined plate current values located in the plate circuit of the tube and adapted to control the crisping and toasting periods of the electric heating elements of an automatic electric crisping and toasting device and a variable resistor connected in parallel circuit with the operating coil of one of said relays and adapted to predetermine the length of the toasting period of such a device.

3. An electron tube control system for an electric crisping and toasting appliance comprising a plurality of toast heating elements connected in series circuit for each slice of bread to be treated, a normally open switch for controlling said heating elements, means to cause closure of said normally open switch to start a crisping operation, an electromagnetically releasable latch for holding said switch closed and a switch for short-circuiting one of said heating elements, said system comprising a grid controlled electron tube, a timing resistor and a timing condenser in the grid circuit of the tube, a voltage doubler bridge source of direct current potential for charging said condenser, two relays in series circuit with each other in the plate circuit of said tube, said source of direct current potential causing a predetermined rate of increase of current traversing said tube and said relays, one of said relays controlling said short-circuiting switch and causing it to operate at a predetermined lower current to terminate a crisping operation, and the other relay controlling said electromagnetically releasable latch to terminate a toasting operation.

4. A system as set forth in claim 3 and including a manually-actuable rheostat connected in parallel circuit with the operating coil of said other relay adapted to predetermine the length of the toasting period of said appliance.

5. An electron tube control system for an electric crisping and toasting appliance, comprising three electric toast heating elements for each toasting chamber, one of said toasting elements being positioned below and along the longitudinal center line of a slice of bread being treated, and the other two elements being positioned one at each side of a slice of bread and substantially parallel with the flat surface thereof, said system comprising a grid controlled electron tube, a timing resistor having a negative temperature coefficient of resistance and being subject to heat from said toast heating elements, a timing condenser in the grid circuit of said tube and two relays having their coils connected in series electric circuit with each other and with the plate of said tube, a source of substantially constant direct current potential and means including said timing resistor, timing condenser and source of direct current potential for causing a predetermined rate of increase of current traversing said tube and the coils of said relays to determine the length of time a slice of bread is subject to low temperature convection heat from all of said toasting elements and then subjected to high temperature radiant heat from the other toasting elements.

6. An electron tube control system as set forth in claim 1 in which said timing resistor is effec-

tive to shorten the length of a toasting cycle as the temperature of the toaster increases.

7. An electron tube control system as set forth in claim 1 in which said timing resistor is effective to shorten the length of a toasting cycle in case of increase of the supply circuit voltage to which said heating elements are connected.

8. In an electric toaster having a plurality of electric toast heating elements for bread crisping and bread toasting, an electric power circuit, 10 an energizing circuit for said heating elements supplied by said power circuit, a timing circuit supplied by said power circuit including a grid controlled electron tube, means supplying a substantially constant direct current potential for the tube grid, a timing resistor and a timing condenser operative to progressively vary the amount of potential delivered to the tube grid so as to cause a predetermined rate of change of plate current traversing the tube, and selectively operative control means for said energizing circuit in series with the tube plate and responsive to two different predetermined values of plate current to determine the length of the crisping and toasting periods of the toaster heating elements.

9. In an electric toaster having a plurality of electric toast heating elements for bread crisping and bread toasting, an electric power circuit, 20 an energizing circuit for said heating elements supplied by said power circuit, a timing circuit supplied by said power circuit including a grid controlled electron tube, means supplying a substantially constant direct current potential for the tube grid, a timing resistor and a timing condenser operative to progressively decrease the amount of potential delivered to the tube grid so as to cause a predetermined rate of increase of plate current traversing the tube, and selectively operative control means for said energizing circuit 30 in series with the tube plate and to two different predetermined values of plate current to determine the length of the crisping and toasting periods of the toaster heating elements.

10. In an electric toaster having a plurality of electric toast heating elements for bread crisping and bread toasting, an electric power circuit, 40 an energizing circuit for said heating elements supplied by said power circuit, a timing circuit supplied by said power circuit including a grid controlled electron tube, means supplying a substantially constant direct current potential for the tube grid, a timing resistor and a timing condenser operative to progressively vary the amount of potential delivered to the tube grid so as to cause a predetermined rate of change of plate current traversing the tube, and a pair of control relays for said energizing circuit in series 50 with the tube plate and being responsive to different predetermined values of the plate current respectively to determine the lengths of the crisping and toasting periods of the toaster heating elements.

11. In an electric toaster having a plurality of electric toast heating elements for bread crisping and bread toasting, an electric power circuit, 60 an energizing circuit for said heating elements supplied by said power circuit, a timing circuit supplied by said power circuit including a grid controlled electron tube, means supplying a substantially constant direct current potential for the tube grid, a timing resistor and a timing condenser operative to progressively vary the amount of potential delivered to the tube grid so as to cause a predetermined rate of change of plate 70 current traversing the tube, and selectively oper-

ative control means for said energizing circuit in series with the tube plate and responsive to two different redetermined values of plate current to determine the length of the crisping and toasting periods of the toaster heating elements, a variable resistor connecting said grid potential supply means with said timing condenser and timing resistor for varying the grid potential and being operable to vary the crisping period and a further variable resistor interconnecting the tube plate and said selectively operative control means and being operable to vary the toasting period.

12. In an electric toaster according to claim 8, the plurality of electric toast heating elements being in series in the energizing circuit and being simultaneously energized during the crisp ing period, and said selectively operative control

means operating to de-energize one of said heat-
ing elements to initiate the toasting period.
